UNITED STATES PATENT OFFICE.

JOHN J. MOLLOY, OF GEORGETOWN, MASSACHUSETTS.

FLEXIBLE WOODEN SHOE-SOLE.

1,270,189.

Specification of Letters Patent. Patented June 18, 1918.

Application filed September 11, 1917. Serial No. 190,771.

To all whom it may concern:

Be it known that I, JOHN J. MOLLOY, a citizen of the United States, residing at Georgetown, in the county of Essex and

5 State of Massachusetts, have invented certain new and useful Improvements in Flexible Wooden Shoe-Soles; and I do hereby declare the following to be a full, clear, and exact description of the invention, such as 10 will enable others skilled in the art to which it appertains to make and use the same.

This invention relates to improvements in a flexible wooden shoe sole and has for one of its objects the provision of a device of 15 this character, which will have substantially the flexibility of an ordinary leather sole, and which will be simple, durable and which can be manufactured and sold at a comparatively low cost.

20 Another object of this invention is the provision of a sole constructed of a pair of sections, which are so connected that they will permit of the sole bending with the foot while walking.

25 A further object of this invention is the provision of means adapted to prevent dirt and other foreign matter from entering or accumulating in the connection between the sections of the sole, obviating the danger of 30 incorrect operation of the connection at all times.

With these and other objects in view as will become more apparent as the description proceeds, the invention consists in certain 35 novel features of construction, combination and arrangement of parts as will be hereinafter more fully described and claimed.

For a complete understanding of my invention, reference is to be had to the following 40 description and accompanying drawing, in which:

Figure 1 is a bottom plan view of a flexible wooden shoe sole constructed in accordance with my invention.

45 Fig. 2 is a side elevation of the same,

Fig. 3 is a detail sectional view illustrating the connection between the sections of the sole,

Fig. 4 is a transverse sectional view illustrating the protector strip secured to the inner face of the sole and adapted to overlie the connection between the sections of the sole,

50 Fig. 5 is a fragmentary sectional view illustrating the connection between the sole and the upper of the shoe,

Fig. 6 is a modified form of hinge connection between the sections of the sole.

Referring to the drawings, the numeral 1 indicates as an entirety, a wooden sole 60 consisting of sections 2 and 3. The upper edge of the sole 1 is recessed as shown at 4 for the purpose of receiving the edges of an upper 5 of a shoe, which may be of any desired character. The edge of the upper 5 65 fits within the recess 4 and is secured therein by fastening means 6 that extend through a binding strip 7 of leather or other suitable material whereby the sole is firmly secured to the upper of the shoe. The section 3 of the sole 1 constitutes an instep portion 8 terminating rearwardly in a heel portion 9. The section 2 forms the ball or tread portion of the sole 1. The sole 1, to form the sections 2 and 3 is beveled at a 75 point of connection between the instep portion 8 and the tread or ball portion of the sole. The section 2 is provided with a beveled portion 11 that co-operates with the beveled portion 12 of the section 3, which permits of the section 2 moving with relation to the section 3, the upper being secured to both sections forms a hinged connection therebetween. The outer faces of the sections 2 and 3 at their point of connection 80 are provided with recesses 13 extending the entire width of the sections and co-operating with each other to receive a protector plate 14 that has each end disposed at right angles to form side flanges 15. The side 90 flanges 15 extend upwardly upon each edge of the sole 1 and are secured by fastening means 16 to the section 2 of the sole so that upon movement of the section 2, the protector plate 14 moves toward and from the 95 section 3, and which protector plate is adapted to prevent the accumulation of dirt and other foreign matter between the beveled faces 11 and 12 of the sections 2 and 3. The inner faces of the sections 2 and 3 adjacent the beveled faces 11 and 12 are provided with a recess 17 to receive a lining strip 18, which may be constructed of any desired material suitable for the purpose, such as rubber or the like, and is secured 100 to the section 2 by fastening means 19. The lining 18 overlies the connection between the sections 2 and 3 so as to prevent the sections from pinching or injuring the foot while the sections 2 and 3 are moved in relation with each other when the sole is conforming to the movement of the foot.

Referring to my modified form of invention as disclosed in Fig. 6, it consists of a V-shaped extension 20 formed upon the section 3 and adapted to be received within a V-shaped recess 21 formed in the section 2, which provides a novel form of hinge connection between the sections 2 and 3 so as to prevent dirt and other foreign matter from working in between the sections and into the shoe.

While I have shown and described the preferred embodiment of my invention, it will be understood that minor changes in construction, combination and arrangement of parts may be made without departing from the spirit and scope of the invention as claimed.

What is claimed is:

A wooden sole for shoes comprising a

tread portion, an instep and heel portion combined, a shoe upper secured to said portions for hingedly connecting the instep and tread portions together, said tread and instep portions having coöperating recesses upon the outer faces thereof, a protector plate disposed within said recesses and overlying the connection between said tread and instep portions, and right angled flanges formed upon the ends of the protector plate and secured to the tread portion.

In testimony whereof I affix my signature in presence of two witnesses.

JOHN J. MOLLOY.
